UNITED STATES PATENT OFFICE.

LOUIS W. CHISM, OF SOUTHBURG, CONNECTICUT, ASSIGNOR TO THE STEEL PRODUCTS COMPANY, OF HARTFORD, CONNECTICUT, A CORPORATION OF CONNECTICUT.

CARRIER APPARATUS.

1,347,496.

Specification of Letters Patent.

Patented July 27, 1920.

Application filed June 12, 1917. Serial No. 174,259.

To all whom it may concern:

Be it known that I, LOUIS W. CHISM, a citizen of the United States, and a resident of Southington, in the county of Hartford and State of Connecticut, have invented an Improvement in Carrier Apparatus, of which the following description, in connection with the accompanying drawings, is a specification, like characters on the drawings representing like parts.

This invention relates to carrier apparatus of the cable propulsion class, and is more particularly concerned with store service apparatus of the so-called high line type, in which the principal portions of the system occupy a high level, while drop stations brought down to a low level at the counters have provision for receiving the carriers from and delivering them to the high level.

My invention will be best understood by reference to the following description, when taken in connection with the accompanying drawings showing two specific embodiments thereof, while its scope will be more particularly pointed out in the appended claims.

In the drawings:

Figure 1 is a side elevation of the upper portion of one form of a carrier apparatus embodying my invention;

Fig. 1^a is a detail sectional view on line 1^a—1^a of Fig. 1;

Fig. 2 is a side elevation of the lower portion of the apparatus shown in Fig. 1, both figures when taken together being considered as one view;

Fig. 3 is a sectional view on line 3—3 of Fig. 2;

Fig. 4 is a plan section on line 4—4 of Fig. 1;

Fig. 4^a is a detail plan section on line 4^a—4^a of Fig. 1;

Figs. 5 and 6 are detail sectional views on an enlarged scale on line 5—5 of Fig. 1, illustrating the transfer of the driving engagement of the carrier from the auxiliary cable to the main cable.

Fig. 7 is a perspective diagram of the cables and pulleys, or wheels, of the apparatus illustrated in Figs. 1 to 6, inclusive;

Fig. 8 is a similar perspective diagram of the cables and pulleys, or wheels, of a modified form of apparatus embodying my invention;

Fig. 9 is a side elevation of the upper portion of the modified form of apparatus;

Fig. 10 is a detail plan section on line 10—10 of Fig. 9; and

Fig. 11 is an end elevation of the modified form of apparatus shown in Figs. 8, 9 and 10.

Referring to Figs. 1 to 7, inclusive, of the drawings, and to the embodiment of my invention which is here shown, the carrier apparatus selected for exemplification comprises a main outgoing track 12 and a main incoming track 13, which, it will be understood, connect a cashier's station, not shown, with one or more outlying sub-stations, of which one is shown for example. The outgoing track 12 is composed of a pair of usual rails, while the incoming track 13 is composed of a pair of usual rails adapted to guide a carrier 14 of usual and well-known construction. Associated with the tracks 12 and 13 is a suitable endless carrier-propelling cable, having an outwardly traveling lead 15 and an inwardly traveling lead 16. The carrier is provided with guides 17, 17, and 18, 18, to receive the rails therebetween. The carrier is also provided with usual and well-known clutching means, comprising a fixed gripper 19 and a spring-controlled gripper 20, which is operated in a well-known manner by closing and opening cams to grip and release the cable.

Additional guides 21 on the sides of the carrier act in a well-known manner to divert the carrier selectively from the main outgoing track into the outlying sub-station to which it belongs.

To this end, the station is provided with usual switch tracks 22, arranged in pairs, two on each side of the carrier and separated from each other by slots 23 to receive the guides 21. These guides, as usual, are placed at various heights upon the carriers, according to the station to which they belong, and the diverting switch tracks 22 are in practice correspondingly placed as to height from the outgoing track 12. Such of the carriers as are not intended for this particular station will pass from left to right (Fig. 1) beneath the diverting switch tracks 22, and travel along to the station to which they belong. Such of the carriers as belong to the particular station shown will be diverted from the outgoing track 10 by the engagement of the guides 21 with the diverting switch tracks 22, so that the carrier, while still maintaining its hold upon

the cable, will be lifted out of coöperation with the track 12, said track for this purpose being provided with usual offset or laterally spread portions 24, to permit the guides 18 5 to clear such track. When the carrier is thus diverted from the main outgoing track, it still maintains its hold on the cable for a time, thus lifting the cable from its normal position shown in Fig. 1.

10 The carrier then passes into coöperation with a drop station receiving track 25. As the carrier passes out of coöperation with the switch tracks 22 into coöperation with the receiving track 25, a usual opening cam 15 26 operates the gripper 20 to release the cable and allow the latter to resume its normal level. The carrier then continues by its momentum down the receiving track 25 to the bottom of the station, where it strikes 20 a buffer 26, and it may then be removed from laterally offset portions 27 of said track.

I will now describe the means whereby carriers may be despatched from this particular station to the main incoming track, 25 and thence along the latter to the cashier's station, and whereby other carriers despatched from a more remote station or stations may pass this particular station on 30 their way to the cashier's station.

An upward despatching track 28, provided with laterally offset portions 29 for the introduction of the carrier in the usual manner, leads from a base 30 at the foot of 35 the station in an upward direction, and curves from a vertical into a horizontal plane at the level of the incoming track 13. Here it extends a short distance horizontally parallel with the track 13, as best seen 40 in Fig. 4, and then curves toward and merges into the track 13, so as to deliver carriers into the latter.

Adjacent the junction of the tracks 13 and 28, I have provided suitable means to 45 maintain the carriers in proper relationship with said tracks, whether the carriers are inward bound along the main incoming track 13 or the branch incoming track 28. To this end, I have provided upper and lower 50 guards 31 and 32, best shown in Figs. 1, 1^a and 4. The upper guard 31 is herein supported on brackets 33 and 34, while the lower guard 32 is supported on brackets 35 and 36. By reference to Fig. 4^a, considered 55 in connection with Figs. 4 and 1^a, it will be observed that the guard 31 is provided with a depending rib 37 extending lengthwise of, and generally parallel with, the track 13, and a second rib 38 extending obliquely with reference to the first and generally parallel with the adjacent portions 60 of the track 28.

By reference to Fig. 4^a, it will be observed that the rib 38 terminates short of 65 the rib 37, so as to allow therebetween a

clearance for an upwardly projecting handle 39 on the cover of the carrier 14, as best seen in Fig. 1^a.

The guard 32 is so placed as to height that the guides 18 of the carrier will ride 70 along the top of said plate, and thus the carrier will be supported thereby whether it be traveling inwardly (to the left, Fig. 4) along the main track 13, or along the branch track 28 into the main incoming track 13. 75 Thus the carrier is prevented from dropping into what would otherwise be open space at the intersection of the main and branch tracks. The upper guard 31, on the other hand, serves as a means to prevent the 80 carrier from rising, or at least from rising to such an extent as to become thrown out of proper relationship with the tracks, as will be evident from an inspection of Fig. 1^a.

85 The construction of these guards bears some similarity to constructions disclosed in co-pending application 331,507, October 17, 1919, a renewal of an application filed June 13, 1912, and application 836,054, May 4, 1914. Certain claims to this subject matter have been presented in these applications.

As a means for propelling carriers in an upward direction along the track 28, and 90 thence horizontally into coöperation with the main incoming track 13, I have herein provided an auxiliary endless cable 40. This cable is herein supported and guided in such a way as to form a horizontal loop 100 41, and a depending vertical loop 42, the latter having an ascending lead 43, to which the grippers 19 and 20 of the carrier 14 are gripped in a usual and well-known manner, when the carrier is to be despatched in 105 an upward direction from the lower portion of the station, as illustrated in Fig. 2, there being provided a usual closing cam 44 to operate the movable gripper 20 in a manner too well known to require further 110 description.

In the present instance, the lower end of the loop 42 is formed, and the tension of the auxiliary cable is maintained, by an idle pulley or wheel 45, the latter being 115 mounted on a shaft 46 journaled in suitable movable bearings 47 carried by a combined pulley guard and weight 48. The latter is in the form of a housing mounted to slide vertically on the rails of the track 28, and 120 upon a pair of suitable rods 49. This housing is made sufficiently heavy to maintain the auxiliary cable 40 under proper tension. The lead 43 passes in an upward direction over idle pulleys or wheels 50 and 51, by 125 means of which its direction is changed from the vertical to the horizontal, as best seen in Fig. 7. The upper horizontal lead 52 of the loop 41 extends from the pulley or wheel 51 to a pulley or wheel 53, by means 130

of which the auxiliary cable is driven. The lower, or returning lead 54 of the loop 41 extends from the pulley 53 to an idle pulley or wheel 55, and from the latter the descending lead 56 of the loop 42 extends to the pulley 45 at the bottom of the loop.

By reference to Fig. 4, it will be observed that the horizontal loop 41 of the auxiliary cable 40 is inclined at an angle to the vertical loop 42, or to put it another way, is at a slight angle with relation to the main track 13 and the inwardly traveling lead 16 of the main cable. All the pulleys or wheels are suitably grooved to receive the cable, but as an additional safeguard to prevent any danger of the horizontal loop 41 escaping from the pulley or wheel 53, the latter is herein provided with an extra deep flange 57, best seen in Figs. 1 and 4.

Heretofore, in the use of store service equipments having auxiliary cables driven by the main cable, some trouble has been experienced owing to the difficulty of supplying power from the main cable to the auxiliary cable without more or less serious slippage. As a means for overcoming these difficulties, I have herein provided the incoming lead 16 of the main cable with a loop 58 of suitable form appropriately connected with the pulley 53 to drive the latter and thus to impart the desired motion to the auxiliary cable. This loop may take other forms, but herein is closed and is formed about two wheels or pulleys only, designated 59 and 60. This loop, it should be observed, extends in the same general direction as the incoming lead 16, but preferably has a downward inclination toward its inner end (toward the left, Figs. 1 and 7). It will also be noted that the two leads of the cable which form the loop 58 cross each other. In the present example, the point of crossing is adjacent the wheel 60, as best shown in Fig. 7, and as the loop has a slight downward inclination toward its left-hand end (Figs. 1, 4 and 7), the pulley 60 is herein provided with a large hub 61, on which one lead of the loop rests. While the pulleys 53 and 59 might actually be made separate and connected, or otherwise suitably secured to each other, I prefer to form them integral, as best seen in Fig. 4.

It is found in practice that with the loop 58 of the described form, there is sufficient arc of contact of the main cable with the pulley 59 to insure the requisite power for the driving of the auxiliary cable, without the slippage which has heretofore caused more or less difficulty in carrier apparatus of this general type.

Owing to the presence of the loop 58 in the main cable, it must be evident that an incoming carrier traveling along the main track 13, propelled by the incoming lead 16 of the main cable, must be disengaged from

the latter and reengaged therewith adjacent the loop 58. To this end, I have herein provided (see Fig. 4) an opening cam 62 in the path of the movable gripper 20 to open the latter thereby to disengage the carrier from the cable, and a closing cam 63 in the path of said gripper to cause the reengagement of the carrier with the cable. At this point, I have provided a dip or depression 64 in the main track 13, operating in a usual and well-known manner to cause the carrier to descend momentarily, so that the cable will be in the proper position between the grippers 19 and 20 when the latter is closed by the closing cam 63. The distance between the opening cam 62 and the closing cam 63 is so very short that the interruption and reestablishment of the driving connection between the carrier and the main cable occurs instantaneously, and without substantial loss of momentum. There is, therefore, no danger of carriers becoming stalled at this point. These cams perform another important function,—that of transferring the driving engagement of carriers from the auxiliary cable 52 to the main incoming lead 16 of the main cable. When a carrier is despatched upwardly along the track 28, it maintains its hold upon the cable 52, and as the carrier passes from the branch track 28 into the main track 13, the grippers draw the auxiliary cable 52 from its normal position shown in Fig. 5 to that which is shown in Fig. 6. The carrier, still maintaining its hold upon the auxiliary cable, travels along the main track 13 until the gripper 20 encounters the opening cam 62, whereupon the latter opens the gripper and releases the auxiliary cable. It should here be noted that I have herein provided a bracket 65, having a depending guard 66 against which the auxiliary cable 52 is brought by the grippers of the carrier when the latter is on the main track, as illustrated in Fig. 6. This prevents interference of the cables and compels the auxiliary cable to snap back into its normal position illustrated in Figs. 4 and 5.

The carrier now continues along under its momentum until it is engaged with the main cable by means of the closing cam 63. To this end, the carrier, having thus been engaged with the main cable, continues on its way to the cashier's station.

Referring now to Figs. 8 to 11, inclusive, I have there shown a carrier apparatus similar in most respects to that hereinbefore described, but modified as to the arrangement of the auxiliary cable, more particularly the depending loop of the latter. This modification is such as to enable me to utilize this form, not merely as a depending drop station, but also as a branch which may descend and then extend laterally in any desired direction so as to serve a counter which is not situated directly beneath or adjacent

120

125

130

to the main tracks. In connection with these figures, for the sake of convenience of comparison with the form first described, I have employed corresponding reference characters for corresponding parts, but with the addition of the index prime (').

In this modification, I provide as before main outgoing and incoming tracks 12' and 13', a carrier 14' propelled along said tracks 10 by outgoing and incoming leads 15' and 16' of a main cable, and having guides 17' and 18' and grippers 19' and 20'. In this case, also, an outward bound carrier belonging to 15 this particular station is diverted from the main outgoing track 12' by diverting switching tracks 22' onto a branch outgoing track 25'. In this form, however, the carrier, after descending the branch outgoing track 25' for a greater or less distance, is power 20 driven to its destination by an auxiliary cable 42'.

This auxiliary cable differs from that previously described, particularly in that the ascending and descending leads of its 25 pending loop are reversed in position, so that the descending lead is associated with the branch outgoing track for the propulsion of carriers therealong. Here, the ascending lead 43' of the pending loop 42' passes in an upward direction over an idle 30 pulley 50'. The upper lead 52' of the horizontal loop 41' extends from the pulley 50' to a pulley 53', while the lower lead 54' extends from the pulley 53' to a pulley 55', 35 and the downwardly traveling lead 56' extends from the latter pulley. It should here be observed that the pulley 55' is of extra wide face (see Fig. 11), and its axis is obliquely disposed so as to bring the lead 54' 40 forward (Fig. 9) beyond the track 28', so as not to interfere with the latter. The angle at which this pulley is set in practice is such that when the cable is moved in the proper direction, it will be maintained in its 45 proper relation with said pulley, as shown in Figs. 9 and 11.

In this form, the pulley 53' is secured to and driven by a pulley 59', and the latter is driven by a loop 58' in the incoming lead 50 16' of the main cable, similar to that hereinbefore described. So, also, in this case, opening and closing cams 62' and 63' are 55 associated with the loop 58' and serve as in the form first described to unclutch inward-bound carriers from and clutch them to the cable. Guards 31' and 32', similar to those hereinbefore described, act in a like manner to maintain the inward bound carriers in proper relationship with the main and branch incoming tracks adjacent the junction of the latter.

I have already stated that in this modification, carriers diverted from the main outgoing track 12' onto the branch outgoing track 25' travel along the latter under their

own momentum for a greater or less distance, and are thence propelled toward their destination by the downwardly traveling lead 56' of the auxiliary cable. To this end, I have provided a closing cam 67, associated with the descending lead 56', so as to clutch the cable grippers 19' and 20' onto the latter. This closing cam may be situated at any suitable point along the branch outgoing track 25'. The latter is herein (see Fig. 11) extended vertically for some distance, and then horizontally to a horizontal station 68. The incoming branch 28' is similarly extended in parallel relationship with the track 25' to the station 68, and the latter is provided with a pulley 45' at the end of the loop 42', this pulley being carried by a suitably combined pulley guard and cable tensioning device 48'. The outward branch 25' is provided with usual offset openings 27' for the removal of the carrier at the station 68, and adjacent these openings there is provided an opening cam 69 to unclutch the carrier from the outward traveling lead 56', after which the carrier is stopped by a buffer 26'; and may then be removed through the openings 27'. To provide for the despatching of a carrier from this station, the track 28' is provided with offset openings 29', and there is provided a closing cam 44' to cause the latter to be clutched to the incoming lead 43' in an obvious manner.

The direction of the branch outgoing and incoming tracks 25' and 28', may be changed from vertical to horizontal by any usual or 100 desired means, such for example as a well-known corner 70 equipped with a pair of co-axially disposed wheels 71 to receive the leads 56' and 43' of the auxiliary cable.

In the operation of this form, as well as that of the form first described, a carrier dispatched from the substation travels along the branch incoming track 28' and from the latter onto the main incoming track 13', and after reaching the latter, its 110 driving engagement is transferred from the auxiliary cable to the main cable by the opening and closing cams 62' and 63', whereupon it continues on its way along the main track.

While I have herein shown and described two specific forms or embodiments of my invention for illustrative purposes, and have disclosed and discussed in detail the constructions and arrangements incidental to two specific applications thereof, it is to be understood that the invention is limited neither to the mere details or relative arrangements of parts, nor to its specific embodiments herein shown, but that extensive deviations from the illustrated forms or embodiments of the invention may be made without departing from the principles thereof.

Having thus described my invention, what

I claim and desire by Letters Patent to secure is:

1. In a carrier apparatus, the combination of a carrier, two carrier-propelling cables one driven by the other, the driving cable being provided with a loop, means driven by said loop for driving said driven cable, and means to interrupt and reestablish the driving connections between said carrier and said driving cable, thereby to permit said carrier to pass said loop without traversing the same.

2. In a carrier apparatus, the combination of a carrier, two carrier-propelling cables one driven by the other, the driving cable being provided with a closed loop, means driven by said loop for driving said driven cable, and means to interrupt and reestablish the driving connection between said carrier and said driving cable within the limits of said loop.

3. In a carrier apparatus, the combination of a carrier, two carrier-propelling cables one driven by the other, the driving cable being provided with a loop, two wheels only about which said loop is formed, means driven by said loop for driving said driven cable, and means to interrupt and reestablish the driving connection between said carrier and said driving cable intermediate the axes of said wheels.

4. In a carrier apparatus, the combination of a carrier, two carrier-propelling cables one driven by the other, the driving cable being provided with a loop, two wheels only about which said loop is formed, a third wheel connected to and driven by one of said two wheels and in turn driving said driven cable, and a track to guide said carrier past said loop without traversing the same.

5. In a carrier apparatus, the combination of a carrier, two carrier-propelling cables one driven by the other, the driving cable being provided with a loop, two wheels forming ends of said loop, means driven by one of said wheels for driving said driven cable, and means to disconnect said carrier from and connect the same with said driving cable between the ends of said loop.

6. In a carrier apparatus, the combination of a carrier, two carrier-propelling cables one driven by the other, the driving cable being provided with a loop, two wheels about which said loop is formed, two leads of said cable forming said loop crossing each other, means driven by one of said wheels for driving said driven cable, and means to interrupt and reestablish the driving connection between said carrier and said driving cable adjacent such crossing.

7. In a carrier apparatus, the combination of two carrier-propelling cables one driven by the other, the driving cable being

provided with a loop, means driven by said loop for driving said driven cable, a carrier, means to transfer driving engagement of said carrier from one to the other of said cables, and means to transfer driving engagement of said carrier from one part of said driving cable to another adjacent said loop.

8. In a carrier apparatus, the combination of two carrier-propelling cables one driven by the other, the driving cable being provided with a loop, two leads of said loop crossing each other, means driven by said loop for driving said driven cable, a carrier, means to transfer driving engagement of said carrier from one to the other of said cables, and means to transfer driving engagement of said carrier from one part of said driving cable on one side of said crossing to another part on the other side of said crossing.

9. In a carrier apparatus, the combination of two carrier-guiding tracks, one delivering carriers to the other, two carrier-propelling cables, one driven by the other, the driving cable being provided with a loop, means driven by said loop for driving said driven cable, and means for causing the transfer of a carrier from one of said tracks to the other and the transfer of the driving engagement of the carrier from one of said cables to the other and from one part of said driving cable to another adjacent said loop.

10. In a carrier apparatus, the combination of a carrier, carrier-propelling means, carrier-guiding means including two tracks, one converging toward and delivering carriers into the other, said tracks having each two rails, one rail of one track merging into and constituting in effect a continuation of one rail of the other track, the remaining adjacent converging rails terminating and forming an apex, and oppositely disposed supplemental carrier-guiding means to receive and guide carriers therebetween past said apex.

11. In a carrier apparatus, the combination of a carrier, carrier-propelling means, carrier-guiding means including two tracks disposed in a horizontal plane, one converging toward and delivering carriers into the other, said tracks having each two rails, one rail of one track merging into and constituting in effect a continuation of one rail of the other track, the remaining adjacent converging rails terminating and forming an apex, and supplemental carrier-guiding means disposed above and below the plane of said tracks to receive and guide carriers therebetween past said apex.

12. In a carrier apparatus, the combination of a carrier, carrier-guiding means, carrier-propelling means including an endless cable having a loop comprising two leads, a

wheel in said loop, and combined cable-tensioning and wheel-guarding means in which said wheel is mounted for travel lengthwise of said loop, said wheel-guarding means having a part disposed intermediate said leads.

13. In a carrier apparatus, the combination of a carrier, carrier-guiding means, carrier-propelling means including an endless cable having a depending loop, a wheel suspended in said loop, and combined cable-tensioning and wheel-guarding means in which said wheel is mounted for travel lengthwise of said loop, said wheel-guarding means comprising a depending wall about said wheel.

14. In a carrier apparatus, the combination of a carrier, carrier-guiding means, carrier-propelling means including an endless cable having a depending loop comprising two leads, a wheel suspended in said loop, and a housing for said wheel, said housing

having its weight sustained by said wheel and constituting a tensioning means for said cable, said housing having a part disposed intermediate said leads and a part depending about said wheel.

15. In a carrier apparatus, the combination of a carrier, carrier-guiding means, carrier-propelling means including an endless cable having a depending loop, a wheel suspended in said loop, and combined cable-tensioning and wheel-guarding means in which said wheel is mounted for travel lengthwise of said loop, said cable-tensioning and cable-guarding means being mounted to slide on and lengthwise of said carrier-guiding means, and having provision to guard the upper part of said wheel and the adjacent portions of said loop.

In testimony whereof I have signed my name to this specification.

LOUIS W. CHISM.
